UNITED STATES PATENT OFFICE

164,141

ART CABINET

Philip F. B. Stahl, Chicago, Ill.

Application May 5, 1950, Serial No. 9,729

Term of patent 14 years

(Cl. D33—19)

To all whom it may concern:

Be it known that I, Philip F. B. Stahl, citizen of the United States of America, residing at Chicago, in the county of Cook, State of Illinois, have invented a new, original, and ornamental Design for Art Cabinet, of which the following is a specification, reference being made to the accompanying drawing, forming part hereof.

Referring to the drawings, Fig. 1 is a front perspective view of an art cabinet embodying my new design in closed position; Fig. 2 is a rear perspective view of the same with the back panels partly open; Fig. 3 is a perspective view of my art cabinet in open position; and Fig. 4 is a perspective view of my art cabinet in open position with the interior parts in position for use.

I claim:
The ornamental design for an art cabinet, substantially as shown.

PHILIP F. B. STAHL.
